FUEL IGNITION SYSTEM

Vernie A. Fox, Detroit, Mich.

Application September 8, 1941, Serial No. 410,018

3 Claims. (CL 158—28)

This invention relates, in general, to ignition systems and, in particular, to one employable in conjunction with fuel ignition.

One of the objects of the present invention is to provide a new and improved fuel ignition system which operates with the highest degree of simplicity, economy and safety and the parts of which are readily and easily inter-assembled or dis-assembled.

Another object is to provide a new and improved fuel ignition system the igniter of which is faultlessly certain to acquire a temperature at least as high as the ignition temperature of the fuel before the latter begins to flow.

Another object is to provide a new and improved fuel ignition system wherein fuel flowage is faultlessly certain to cease in the event of ignition failure.

Another object is to provide a new and improved fuel ignition system which is unaffected by local pressure conditions, such as suction or drafts.

Another object is to provide a new and improved fuel ignition system wherein the parts are simple and inexpensive in construction and novel and compact in arrangement.

Other objects and advantages of the invention will become readily apparent from a reference to the following specification taken in conjunction with the accompanying drawing, wherein:

Figure 1 is a longitudinal sectional view of my new and improved igniter device;

Figures 2 and 3 are sections taken along the lines 2—2 and 3—3, respectively, in Figure 1;

Figure 4 is a diagrammatical view of a system which is particularly adapted for having my device incorporated therewith; and

Figure 5 is an elevational view of my device shown in a slightly different use than in Figure 4.

My igniter consists of a tubular shell, support, body, guard or duct 10 which is open at its ends and carries therebetween, preferably permanently, a fuel inlet-forming member 12 through which fuel may flow (from a source to be described) for entering the interior of said duct, and, if desired, the flow path defined by said member may have installed therein a section of mesh 14 for preventing foreign matter from travelling therewith. One of the two ends of duct 10 is to serve as a flame outlet therefor, and this outlet may be supplemented, if desired, by other outlets 16 formed through and around the wall of said duct adjacent said one end.

The opposite end of duct 10 is formed to carry,

either removably or irremovably, and be closed by an insulated cap, cover or support 18 which provides an anchorage for a pair of terminal posts 20 and 22, these posts having bar-like conductors 24 and 26 secured thereto in electrical continuity therewith and extending forwardly therefrom in spaced relation to each other into positions intermediate the flame outlet end of said duct and the fuel inlet thereof. The forward ends of conductors 24 and 26 are bifurcated, as at 28 and 30, respectively, so as to provide for the holding of a resistance coil 32, one end of said coil residing between the arms of said bifurcated portion 28 and the other end residing between the arms of said bifurcated portion 30, the coil proper extending forwardly toward the flame outlet end of duct 10. As shown, fasteners 34 are employed for tightening the arms of portions 28 and 30 with respect to the ends of coil 32 held thereby. Furthermore, an insulated support 36 is carried within duct 10 to receive portions 28 and 30 and hold same in place with respect to each other, said support having a substantially tight fit with the inner wall of said duct and being formed therethrough and therearound with ports 38 for intercommunicating the interior portions of said duct on opposite sides of said support.

Before discussing the operation of the igniter device hereabove described, attention is directed to Fig. 4, wherein said device is shown as being employed in conjunction with a standard fuel burner 40, said burner having its inlet connected, as is usual, to the outlet of a standard manifold or air-fuel mixing device 42, and the lower end of fuel inlet-forming member 12 of said igniter device, which may be cut on the bias to enhance fuel flow thereto and threaded, being received within and secured to the wall of said device 42 and producing an operative relationship between the flame outlets of said igniter device and said burner. The air-fuel mixing chamber provided within manifold 42 carries a standard fuel jet 44 which is fed with fuel through the proper tubing, shown at 46, leading from the source (not shown) of fluid fuel at hand. If desired, tubing 46 may be provided with a standard, manually operable valve 48 by means of which fluid flow into manifold 42 may be selectively controlled. And, between valve 48 and manifold 42 tubing 46 is adapted to carry an electrically operable valve, shown generally at 50, this valve 50 being more or less standard in design in that it is equipped with a chamber 52 in direct communication with the outlet side of said valve 48, a

chamber 54 in direct communication with said manifold, a valve member 56 operable for controlling fuel flow from said chamber 52 into said chamber 54, a core 58 secured to said valve member 56 for movement therewith, a magnet body 60 receiving said core and energizable to move same, and a coil 62 operable for energizing said magnet. Incidentally, the normal position of valve member 56 is that whereat chambers 52 and 54 are cut off from each other, this condition existing during electrical inactivity of coil 62.

Still referring to Figure 4, it will be seen that I provide a transformer, generally indicated at 64, which is of the step-down type because I intend using a current of relatively low voltage for energizing the coil 32 of my igniter device, this transformer having a primary 66 connected across a service line 68 and a secondary 70 connected by means of leads 72 and 74 to the posts 22 and 20 of said device. Line 68 preferably has a switch 76 arranged therein whereby the energization of primary 66 may be controlled, and it is to be noted that said switch is the sole controlling means for coil 32; in other words, regardless of what happens in the system described herebelow, when switch 76 is closed, coil 32 is energized, and, when switch 76 is open, coil 32 is de-energized. And, when coil 32 is energized by the closing of switch 76, the fuel-air mixture passing through member 12, into duct 10, through ports 38, and into contact with said coil, will become ignited and the resulting flame will be emitted through the outlet end and other outlets 16 of said duct, there to ignite the fuel-air mixture being emitted from burner 40 and thus serve for the most part as a pilot burner.

A relay, generally indicated at 78, has its coil 80 connected in the secondary circuit in series with secondary 70 and coil 32, namely, in the lead 72 which interconnects one side of said secondary and one side of said coil 32, said relay having, in addition to said coil 80, a magnet 82 which is energizable responsive to energization of said coil 80, a core 84 which is movable responsive to energization of said magnet, and a switch element 86 which is carried by said core for movement therewith. Switch element 86, upon energization of coil 80 responsive to the closing of switch 76 and the resulting energization of secondary 70, is adapted to close a break existing during de-energization of said coil in a lead 88 which is connected at one of its ends to one side of primary 66 and at the other of its ends to another switch element 90 (which is to be described presently). One end of another lead 92 is connected to the opposite side of primary 66, and the opposite end of this lead is connected to one side of the coil 94 of a relay, generally indicated at 96 and to be described presently, the opposite side of said coil being connected by means of a lead 98 to the aforementioned switch element 90. It is seen, therefore, that the closing of switch 76 energizes coils 80 and 32 and that the energization of said coil 80 simultaneously effectuates the closing of the gap in lead 88 by means of the resulting movement of switch element 86, the result being that energy flows from one side of primary 66 through the two sections of said lead 88 and the intermediate switch element 86 to switch element 90 and back to said primary from said switch element 90 through lead 98, coil 94 and lead 92.

Series circuit 66-88-86-88-90-98-94-92-66, which is closed simultaneously with the

closing of series circuit 70-72-80-72-32-74-70, is employed for the purpose of bringing relay 96 into play, the effect of which is to be described presently. This relay is of the delayed action type (the reason, as will soon be seen, being to provide a time interval between the energizing of coil 32 and the opening of valve 50) and is of standard construction, having a magnet 100 which is operable at a predetermined period following the initiation of energy flow through coil 94 for moving a spring-held switch element 102 into play to close a circuit which will soon be described. Switch element 102 has one of its ends permanently connected to an end of a lead 104 connected to lead 88 between switch elements 86 and 90, and the other end of said element 102 is adapted, upon effective energization of magnet 100, to be drawn, against the force of a spring 106, into connection with one end of a lead 108 the other end of which is connected to one side of a solenoid coil 110. The other side of coil 110 is connected to lead 92, which interconnects one side of primary 66 and one side of coil 94, by means of leads 112 and 114.

When magnet 100 becomes effective to cause interconnection of leads 104 and 108 by means of switch element 102, coil 110 becomes energized and actuates a core 116 to which switch element 90 is fixedly connected, and this element 90, to which lead 88 is permanently but resiliently connected, is drawn out of connection with lead 98 and into simultaneous connection with an end of each of two other leads 118 and 120, the other end of said lead 118 being connected to said lead 108 between switch element 102 and said coil 110, and the other end of said lead 120 being connected to one side of coil 62 of electrically operable valve 50. The other side of coil 62 is connected to primary 66 by means of a lead 122 which is connected to leads 112 and 114.

In short, when switch 76 is closed, igniter element 32 becomes energized and, in addition, switch 86 is caused to close the circuit 66-88-86-88-90-98-94-92-66 which includes coil 94. Upon the expiration thereafter of a predetermined period (which is, of course, sufficient to permit the temperature of coil 32 to reach a value at least equal to the ignition temperature of the fuel-air mixture which is to pass through duct 10 from manifold 42 upon the opening of valve 50), magnet 100 becomes capable of drawing switch 102 into contact with lead 108 and thereby place coil 110 in readiness for energization and the job of moving switch 90 from its position of contact with lead 98 into position of contact with leads 118 and 120. The circuit which is closed under the influence of magnet 100 is 66-88-86-88-104-102-108-110-112-114-92-66 and may be termed an "initiating" circuit for coil 110, for it is reopened immediately upon the breakage of the contact between switch 90 and lead 98 which is influenced by the energization of said coil. However, the energization of coil 110 continues after the reopening of the "initiating" circuit therefor, because switch 90 will have closed a "continuing" circuit for said coil, namely, 66-88-86-88-90-118-108-110-112-114-92-66. And, closed simultaneously with the closing of this last mentioned circuit is the parallel "valve" circuit 66-88-86-88-90-120-62-122-114-92-66 in which is contained the coil 62 by the energization of which the chambers 52 and 54 in valve 50 are intercommunicated.

The system, therefore, is one wherein the igniter device is of simple, compact and inexpensive construction and the operation of which is economical and gives to said system the highest degree of automaticity and safety under all conditions. The igniter coil 32 is controlled exclusively by switch 76. The igniter coil 32 is caused to acquire the safe and proper temperature before any ignitable fluid is allowed to pass through any part of the system. And, if an electrical break occurs in the circuit which contains the igniter coil 32, all of the circuits which contain the transformer primary 66 are opened by the switch 86, which means that there is never any fuel flowage throughout any part of the system during electrical inactivity of said coil 32.

Whereas Figure 4 shows the igniter device employed as a pilot burner for the main burner 40, Fig. 5 shows it connected, if desired, directly to the manifold 42 so that the mixture passes in its entirety through duct 10 rather than as in said Figure 4.

Although the invention has been described with some detail it is to be understood that such description is for the purpose of illustration only and is not to be taken as definitive of the limits of the inventive idea. The right is reserved to make such changes in the details of construction and arrangement of parts as will fall within the purview of the attached claims.

What I claim is:

1. In a fuel ignition system comprising an igniter circuit and a control circuit, a continuously energized igniter in said igniter circuit adapted to be mounted in the path of fuel flow, a magnetically controlled normally open valve in said control circuit for controlling the flow of fuel in said flow path, a time delay circuit interposed between the control circuit and the igniter circuit, relay switch means in the igniter circuit for closing said time delay circuit upon energization of the igniter circuit, a holding circuit for said control circuit, a time delay relay switch in said time delay circuit for closing said holding circuit a predetermined time interval after the closing of said time delay circuit, a holding circuit for the first-mentioned holding circuit, and a relay switch in said first-mentioned holding circuit for closing said second-mentioned holding circuit to thereby energize the electromagnetically controlled valve and hold said valve in an open position to permit fuel flow along said flow path.

2. In a fuel ignition system comprising an igniter circuit and a control circuit, a continuously energized igniter in said ignition circuit adapted to be mounted in the path of fuel flow, a normally closed electromagnetically controlled valve in said control circuit for controlling the flow of fluid in said flow path, a time delay circuit interposed between said igniter circuit and said control circuit, a relay switch operable upon energization of the ignition circuit for energizing said time delay circuit, a time delay solenoid in said time delay circuit, normally closed switch means in said time delay circuit, a holding circuit for said control circuit adapted to be closed upon the energization of said time delay circuit after a predetermined time interval, switch means in said holding circuit operable upon energization of said time delay solenoid for closing said holding circuit, a holding relay in said holding circuit for controlling said normally closed switch means to interrupt said time delay circuit upon energization of said holding circuit, and a holding circuit for the first-mentioned holding circuit controlled by the holding relay therein for holding the first-mentioned holding circuit closed and the electromagnetically controlled valve open.
3. In a fuel ignition system comprising an igniter circuit and a control circuit, a continuously energized igniter element in said igniter circuit adapted to be mounted in the path of fuel flow, a magnetically controlled valve in said control circuit for controlling the flow of fuel in said flow path, a time delay circuit interposed between the control circuit and the igniter circuit, a relay switch in said igniter circuit for closing said time delay circuit when said igniter circuit is energized, a holding circuit for said control circuit, a time delay relay element in the time delay circuit adapted to energize the holding circuit a predetermined time interval after energization of said time delay relay element, a holding relay in said holding circuit, a second holding circuit for said electromagnetically controlled valve, and switch means controlled by said holding relay for interrupting the time delay circuit and maintaining said second-mentioned holding circuit closed, whereby said magnetically controlled valve will be opened after the igniter has reached a state of incandescence and will be held in an open position until failure of said igniter element.

VERNIE A. FOX.
